United States Patent Office

Des. 229,513

Patented Dec. 4, 1973

229,513

COMBINED KEYBOARD AND ELECTRONIC DATA PRINTER

Harold William Bermender, Jr., Hamden, Conn., assignor
to Mite Corporation, New Haven, Conn.

Filed July 1, 1971, Ser. No. 159,092

Term of patent 7 years

Int. Cl. D18—02

U.S. Cl. D64—11 R

FIG. 1

FIG. 4

FIG. 3

FIG. 2

FIG. 1 is a three-quarter perspective view of a combined keyboard and electronic data printer showing my new design;

FIG. 2 is an elevational view of the opposite side thereof;

FIG. 3 is a rear elevational view thereof; and

FIG. 4 is a bottom plan view thereof.

I claim:

The ornamental design for a combined keyboard and electronic data printer, as shown.
